UNITED STATES PATENT OFFICE

136,201

DESIGN FOR A POULTRY WATERING DRIP FOUNTAIN

Charles Brodsky, Brooklyn, N. Y.

Application June 5, 1943, Serial No. 110,371

Term of patent 14 years

To all whom it may concern:

Be it known that I, Charles Brodsky, a citizen of the United States, residing at Brooklyn, in the county of Kings and State of New York, have invented a new, original, and ornamental Design for a Poultry Watering Drip Fountain, of which the following is a specification, reference being had to the accompanying drawing, forming part thereof.

Figure 1 is a side elevational view of a poultry watering drip fountain showing my new design, and

Figure 2 is a top plan view thereof.

I claim:

The ornamental design for a poultry watering drip fountain, as shown.

CHARLES BRODSKY.
